BED SHEET CONSTRUCTION

Bertha Berman, New York, N. Y.

Application December 9, 1947, Serial No. 790,559

4 Claims. (Cl. 5—335)

1

This invention relates to removable covers for mattresses, cushions and the like, and more particularly is directed to an improved bed sheet construction.

Among the objects of the invention is to provide an improved cover of the character described which shall be simple in construction, which shall be inexpensive to manufacture yet durable, which shall be easy and convenient to make up into a neatly appearing, snug fitting cover, which shall smoothly overlie the top, horizontal side, head, foot and vertical sides of a mattress and be readily replaceable, which shall in unfolded condition lend itself to frequent dry cleaning or laundering operations, and which shall be efficient and practical to a high degree in use.

Other objects of the invention will in part be obvious and in part hereinafter pointed out.

The invention accordingly consists of features of construction, combination of elements and arrangements of parts which will be exemplified in the construction hereinafter disclosed, the scope of the application of which will be indicated in the claims following.

In the accompanying drawing in which one embodiment of the invention is shown,

Fig. 1 is a top plan view of the improved bed sheet construction embodying the invention fitted in effective position on mattress of conventional manufacture, partly broken away to expose the top horizontal side of the mattress.

Fig. 2 is a top plan view of the bed sheet shown in Fig. 1 unfolded in outstretched condition.

Fig. 3 is a fragmentary perspective view of one corner of the mattress, showing the position of the improved bed sheet during the fitting thereof, and

Fig. 4 is a fragmentary perspective view similar to Fig. 3 showing the improved bed sheet completely fitted in position.

Referring in detail to the drawing, 10 denotes a removable cover of improved construction embodying the invention in the form of a bed sheet which is adapted to snugly fit over the horizontal top, vertical sides, and ends of a mattress M of any well understood manufacture.

Bed sheet 10 may be made of cotton, linen or other suitable sheeting material that is limp adapted to be readily dry cleaned or laundered and as seen in Figs. 1 and 2 comprises a rectangular center sheet area 11 extending over said mattress topside, that is, as shown in Fig. 2, over the area between transversely extending

2

fold lines 11a, which are seen to terminate at the opposite rim edges of cover 10 and longitudinally extending fold lines 11b, which are seen to terminate on fold lines 11a. Said fold lines 11a in the drawing indicate the division between center sheet area 11 and spaced apart transversely extending marginal end areas 13 but normally do not form creases. The latter, as shown in Figs. 3 and 4, may be of sufficient dimensions to cover vertical ends of the mattress M. Longitudinally extending fold lines 11b in the drawing indicate the division between the center sheet area 11 and spaced apart longitudinally extending marginal side areas 12, the latter being of sufficient dimensions to cover the vertical sides of the mattress M.

Each marginal end area 13 may terminate in spaced corner forming portions or flaps 13a, of substantially square contour having dimensions 20 corresponding to the thickness of mattress M, and inwardly of each of said corner flaps 13a there is provided a cut away portion or recess 13b terminating short of fold line 11 as shown in Fig. 3 which forms a fold fitting means in 25 the region bordering recess 13b for cover 10 as is hereinafter described.

The rim border edge of the cover 10 may be finished to make it non-ravelling by providing selvages or sewn or heat sealed hems of any 30 well known construction.

In Figs. 2, 3 and 4 rim edges 10a border along said marginal side area 12 and on flap 13a are shown finished with a selvage, while rim edges 10b bordering on marginal end area 13, on recesses 13b and on flaps 13a, are shown to be 35 hemmed by sewing or heat sealing.

Suitable readily releasable fastener means, such as zippers, hooks and eyes or the like may be provided by securing to the underside of 40 flaps 13a one of the complementary or mating elements thereof along hem 10b from the rim edge 13c and as shown in Figs. 2, 3 and 4 spaced apart male elements 14a of snap fasteners 14 are there used. Female snap fastener elements 45 14b are provided to extend in a transverse direction with respect to male elements 14a and spaced therefrom as shown in Fig. 2.

The rim edge 13c of recess 13b bordering along flap 13a may be provided with a tuck 15 which 50 serves to predetermine a smooth upper edge fold 15a as is clear from Figs. 3 and 4.

After constructing the cover 10 in the form of a sheet as described above to the dimensions of mattress M as shown in the drawing, the 55 practical utility is apparent.

The sheet 10 is centered on the top horizontal side of the mattress. The opposite side marginal areas 12 are down folded on fold lines 11b to cover the vertical sides of the mattress M as shown in Fig. 3. The opposite end marginal areas 13 are next down folded on fold lines 11a and also an infold is made as indicated at 16 in Figs. 2 and 3 on said area 13 over each recess 13b, thereby bringing each flap 13a to overlie the portion of area 13 with recesses 13b. The male elements 14a of fastener 14 will then be in registering alignment with female elements 14b and when interlocked secure the flap 13a in position to form neat, smooth corners as is clear from Figs. 3 and 4.

The sheet 10 with the fastener elements 14a detached from 14b becomes loose and unfolded and may be easily removed.

The improved sheet 10 lends itself to laundering operations particularly to ironing without unnecessary wrinkling yet permitting desirable folding as is clear from Fig. 2.

It is to be understood that while the snap fasteners are shown attached directly to the material of sheet 10 such fasteners may also be supplied permanently attached to suitable tapes and said tapes sewn or otherwise secured in same position as shown in the drawing.

It is also to be understood that while the corner flaps 13a are shown to overlie the recesses 13b formed in the marginal end areas 13, such recesses could, if desired, be formed in the marginal side areas 12 and the corner flaps folding along the sides. The sheet construction shown in the drawing is adapted for use on a mattress where the sides are fully exposed and a neat covering is desired.

It will thus be seen that there is provided a sheet construction whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A cover construction of limp material substantially rectangular in shape when spread flat having a center area, end marginal areas, and side marginal areas adapted to cover a horizontal

5 side, vertical ends and vertical sides, respectively, of an article so shaped when folded along lines bordering said center area, said marginal areas terminating in spaced end flaps and being formed with a rim edge polygonally shaped recess adjacent each flap extending toward one of said fold lines and terminating short of the latter to provide a marginal area portion for extending to cover the article edge when said flap is folded to overlie said recess, elements of fastening means carried along an underside of each of said end flaps and cooperating elements of said fastening means carried along an upper side of said end areas adjacent each of the recesses.

10 2. A sheet construction comprising a center area for covering a horizontal side of a mattress, end and side marginal areas to cover vertical ends and sides of the mattress, respectively, when folded along lines bordering said center area, 15 an end flap terminating one of said side marginal areas, one of said end marginal areas being formed with a rim edge polygonally shaped recess adjacent said flap extending towards one of said fold lines and terminating short of the latter to provide a marginal area portion for extending to cover the mattress edge when said flap is folded to overlie said recess, and fastening means carried along a rim edge of said flap on one side of said sheet and along a rim edge of said recess on the other side of said sheet for releasably securing said flap in said folded position to form a fitted corner.

20 3. A sheet construction as defined in claim 2 in which said fastening means along the rim edge 25 of said flap extends in right angle relation with respect to the corresponding fastening means extending along the rim edge of the recess when said sheet is spread unfolded.

30 4. The sheet construction defined in claim 2 in which a permanent under-tuck is provided in the portion of the rim edge border of said recess adjacent said flap to determine a smooth upper edge fold when said end flap is folded to overlie the recessed portion.

45 BERTHA BERMAN.
